UNITED STATES PATENT OFFICE

2,434,783

HOBBYHORSE

Robert T. Athey, Armona, Calif.

Application June 7, 1944, Serial No. 539,081

4 Claims. (Cl. 272—52)

1

This invention relates to figure toys and has more specific reference to the style generally referred to in the trade as hobbyhorses and the like. I am not unmindful that hobbyhorses similar to those which I am about to disclose and describe are not new. In fact, I am familiar with the patent to S. J. Cattelin et al., No. 1,668,190, another patent to S. N. Holman No. 2,129,176, and analogous patents in the same field of invention. Keeping this in mind, it will be evident that my primary aim is to structurally, functionally and otherwise improve upon hobbyhorses of the aforementioned patented and similar marketed types and forms.

Briefly, novelty is predicated on a hobbyhorse characterized by transverse parallel base blocks with a flat spring therebetween, a superposed seat-equipped occupant accommodating and exercising spring, and a new and novel block connection between adjacent ends of the springs, the block being characterized by unusual shape to provide desired balance and flexibility in its peculiar coaction with the supplemental springs.

More specifically, novelty has to do with a block which is shaped at its outer end and formed with a segmental curved inner end, the latter coacting with the underlying spring in bowing the same to promote greater flexibility while at the same time maintaining the desired degree of stability.

A further phase of the invention has to do with a clevis carried by the spacing block between the springs, this having its bight portion arching over and spaced from the upper exercising spring to promote greater freedom of action of the spring while at the same time maintaining it in longitudinal alignment with the block on which it is anchored and fulcrumed.

Novelty is also predicated upon the manner in which a seat provided with a horse's head is attached to the free end of the bouncing or exercising spring, the horse's head being bracketed in a keeper groove for promotion and strength and durability.

It is believed too, that the provision of an ornamental or figure toy seat of the aforementioned type which is adjustably mounted on the bouncing spring is a feature of moment.

Other features and advantages will become more readily apparent from the following description and the accompanying drawings.

In the drawings, wherein like numerals are employed to designate like parts throughout the same—

Figure 1 is a side elevational view of a toy

2

hobbyhorse constructed in accordance with the structural principles of the instant invention.

Figure 2 is a top plan view thereof.

Figure 3 is an enlarged transverse vertical section on the plane of the line 3—3 of Figure 1.

Figures 4 and 5 are cross-sections on the lines 4—4 and 5—5, respectively, of Figure 1 looking in the direction of the arrows.

Figure 6 is an enlarged fragmentary detail section on the plane of the line 6—6 of Figure 1.

Figure 7 is a perspective view of the specially designed assembling, spacing and spring-bending and fulcruming block.

Referring now to the drawings by distinguishing reference numerals it will be seen that the horizontal flat spring 8 has its end portions seated in notches and secured by fastenings 9 to the blocks 10. The superposed coacting exercising or bouncing spring, which is also a flat spring of appropriate dimensions and strength, is denoted by the numeral 11. Importance is attached to the manner of securing the springs and associating the same in companion relationship. As before pointed out, this is accomplished through the medium of an especially designed or fashioned anchoring and assembling block 12. As shown in Fig. 7, the main bottom is plain and rectilinearly straight as indicated at 13. One end is reduced and flattened on its top as indicated at 14. The top surface 15 is parallel to the surface 13 and joins the reduced end portion by way of an incline or declivity 16. The end, which may be identified as the inner end, is rounded to assume an arcuate formation as indicated at 17. This constitutes a rocker and its cam action exerts a downward pressure on the underlying spring 8, thus bowing or flexing said spring downwardly. The block as a unit is bolted or otherwise secured intermediate its end to the spring 8 as indicated at 18. The laterally directed end 19 of the spring 11 rests upon the step 14 where it is fastened thereto as at 20. This fastening passes through the step 14 and spring 8 and into the block 10. The adjacent portion of the spring 11 rests upon the declivity as indicated at 21. At the point where it projects beyond said declivity and over and beyond the flat surface 15 it is assembled by a clevis 22 fastened as at 23. The clevis is sufficiently large to straddle over the spring. In other words, the bight portion thereof is spaced from the spring and the clevis is somewhat diagonally disposed, being at right angles to the spring 11. This clevis serves to allow the spring 11 to play and "float," as it were. At the same time the clevis snugly keeps the

55

spring 11 in alignment with the block, that is, the spacer block 12.

I next call attention to the seat board 24 of general-rectangular form, this having a channel or groove in its bottom as at 25 (see Figure 4). Cross-straps 26 suitably fasten to the board to bridge the channel and serve to hold the spring 11 therein. At the same time, this assemblage may be such as to permit the board to be shifted up and down in relation to the spring, that is, longitudinally adjusted. It will be seen in Figure 1 that two of such fastenings 26 are provided. The horse's head 27 has its lower end seated in an accommodation or adapter channel 28 (see Figure 6) which is provided therefor in the top or median portion of the seat board 24. Pairs of L-shaped brackets 29 on opposite sides serve to assemble and secure the parts 24 and 27 together in firm and reliable relationship.

The numeral 30 designates a foot-piece held in place by an adjusting and clamping bracket 31 and the numeral 27a designates handle bars carried by the horse's head. The entire unit comprising the horse's head and seat board can be adjusted, and the foot-piece can also be adjusted in respect thereto. Therefore, all of the parts have been very carefully chosen and structurally coordinated to provide an overall structure which is aptly fitted for the intended purposes.

As an optional phase of the invention I now direct attention to an auxiliary spring (see Figures 1 and 2) denoted, as a unit by the numeral 32. This underlies the main spring 11 as at 33 and is of any appropriate length. It is provided centrally with a cross piece 34 carrying a clevis 35 which saddles over said spring 11. It is also provided at opposite ends with upstanding laterally directed retention lugs 36 which keep it in proper alignment. This spring unit 32 is adjusted up or down on the spring 11 to strengthen the same at the desired points, whereby to thus increase the utility of the device.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. A hobbyhorse of the class described comprising a horizontally elongated base, a rectilinearly straight and flat exercising spring, a seat-board mounted on one end of said spring, a spacing block secured to one end of said base, said spacing block having its outer end formed into a reduced step, its inner under-face formed into a curvate rocker, and its intermediate portion formed into a declivity merging into said reduced step, the adjacent end of said exercising spring being secured to said step and resting on said declivity.

2. As a new article of manufacture and as a component part of a hobbyhorse construction of the class described, an especially designed and fashioned anchoring and assembling block for an exercising spring, said block being adapted to be interposed between one end of the exercising spring and an underlying horizontally elongated base, said block comprising a substantially rectangular body, the main portion of the bottom of said block being rectilinearly straight, one end being reduced in cross-section and flattened on the top, this being parallel to said rectilinearly straight bottom and constituting a step, the opposite end of the top portion of said block being flat and parallel to said rectilinearly straight bottom, the intermediate portion of the top of said block being inclined rearwardly and outwardly and merging into said step, the frontal end portion of said block being rounded into arcuate form and constituting a rocker.

3. In a hobbyhorse of the class described, a horizontally elongated relatively fixed base, a spacing block superimposed on and secured to one end portion of said base, a rectilinear leaf spring secured at one end to said block, the opposite end overlying the base, a seat secured to said last-named end, and an adjustable, longitudinally shiftable spring-strengthening attachment, said attachment being an independent unit and comprising an auxiliary longitudinally elongated flat spring, this underlying the intermediate portion of said leaf spring and being considerably shorter than said leaf spring and having outstanding opposed pairs of detents at opposite ends, said detents resting against and embracing the longitudinal edge portions of said first-named spring, and a clevis carried by said auxiliary spring and saddling over said first-named spring, whereby to permit the auxiliary spring to be adjusted longitudinally in relation to the other spring to stiffen same wherever necessary or desired.

4. The structure specified in claim 1, said base embodying an elongated horizontally disposed flat spring, and risers attached to opposite end portions of said spring.
